UNITED STATES PATENT OFFICE.

WILLARD E. SWIFT, OF WORCESTER, MASSACHUSETTS, ASSIGNOR TO UNITED STATES ENVELOPE COMPANY, OF SPRINGFIELD, MASSACHUSETTS, A CORPORATION OF MAINE.

CABINET FOR PAPER DRINKING-CUPS.

1,379,228.

Specification of Letters Patent. Patented May 24, 1921.

Application filed June 15, 1912. Serial No. 703,807.

To all whom it may concern:

Be it known that I, WILLARD E. SWIFT, a citizen of the United States, residing at Worcester, in the county of Worcester and 5 Commonwealth of Massachusetts, have invented a new and useful Improvement in a Cabinet for Paper Drinking-Cups, of which the following is a specification accompanied by drawings forming a part of the same.

10 My invention relates to a cabinet adapted to hold a stack of paper drinking cups and having means for the removal of individual drinking cups as they are required for use. My invention is hereinafter described and 15 represented in the accompanying drawings as embodied in a preferred form of construction, by which the cups are held and protected from dust and from contact with the hands of the users, the novel features 20 being pointed out in the annexed claim.

Referring to the accompanying drawings, Figure 1 represents a perspective view of a cabinet embodying my invention.

Fig. 2 is a vertical sectional view. 25 Fig. 3 is a transverse sectional view on the plane of the broken line 3—3, Fig. 2.

Fig. 4 represents the outline of a paper drinking cup adapted to be held in the cabinet represented in Figs. 1 to 3.

30 Similar reference characters refer to similar parts in the different figures.

The cabinet embodying my present invention is particularly designed to contain drinking cups which are collapsed, and in 35 their collapsed form are wider at one end than the other, as represented at A, Fig. 4, having divergent sides 1, making the top 3 of the cup wider than the bottom 2. The cup represented in Fig. 4 has its top edge

40 curved with one side cut away at 4 to form a thumb opening and facilitate in the separation of the sides of the cup.

The cabinet represented in the accompanying drawings comprises a case 5 having 45 parallel vertical sides 6, 6 and a vertical back 7 provided with flanges 8, 8 which are attached to the sides 6, 6 by rivets 9, 9. At the rear vertical edges of the flanges 8, 8 the casing is provided with outwardly 50 turned flanges 10, 10 by which the cabinet may be attached to a vertical wall by screws through the screw holes 11, 11. The lower end of the chamber inclosed in the casing 5 is nearly closed by an inclined bottom 12, 55 leaving a narrow slot or opening 13 between

the lower edge of the bottom 12 and the lower edge of the vertical back 7 of the casing, said opening 13 being of sufficient height to allow a single drinking cup to pass freely. The central portion of the lower 60 edge of the inclined bottom is cut away at 14 to provide an opening for the admission of the thumb or finger of the operator in seizing the edge of a paper cup.

Within the casing 5 are the vertical side 65 walls 15, 15 having flanges 16, 16 which are attached to the vertical back 7 of the casing. The sides 15 are also attached by rivets 17 to the sides 6, 6 of the casing and near their front edges and from the sides of the casing 70 the sides 15 are bent inwardly forming flanges 18, 18. The space inclosed between the flanges 18 and the vertical back 7 and between the inclined side walls 15, 15 has a shape corresponding to that of the paper 75 cup represented in Fig. 4, allowing a stack of paper cups to be held therein in the position indicated by the broken lines 19 Fig. 3.

The front 20 and top 21 of the casing 5 are formed from a single piece provided 80 with flanges 22, 23 which overlap the sides of the casing, the single piece forming a cover for the front and top of the casing which is hinged to the bottom 12 by hinges 24. The hinged cover is retained in a closed 85 position by means of a staple 25, hasp 26 and padlock 27. The inclined side walls 15 extend from the top of the casing to the lower edge of the vertical back 7, leaving a space 28 of uniform width between the lower 90 edges of the sides 15 and the bottom 12 to enable the lowermost drinking cup in the stack to be withdrawn through the opening 13.

At the rear of the vertical back 7 I place 95 a pair of elastic blade springs 29, having attached to their lower ends semicircular rubber blocks 30 which enter through openings 31 in the vertical back 7 and are adapted to press against the rear edges of the 100 drinking cups in the lower portion of the stack immediately above the lowermost cup in the stack. The tension of the springs 29 may be adjusted by means of nuts 32 carried on screw threaded bolts 33 which are held 105 in the vertical back 7. The vertical wall to which the cabinet is attached is represented in Figs. 2 and 3 by the line 34—34, and the flanges 8 are of sufficient width to bring the vertical back 7 and opening 13 suf- 110

ficiently far from the wall 34 to enable the lowermost cups in the cabinet to be withdrawn.

The cabinet is filled by swinging back the hinged cover and filling the space between the inclined side walls 15 with paper cups in the position represented by the broken lines 19. The cover is then closed and the bottom of the lowermost cup presented at the opening 13 is seized by the operator and withdrawn from the cabinet. A weight is preferably placed on the top of the stack and, as the lowermost cup is withdrawn, the entire stack is moved downward by the weight, bringing the next succeeding cup into position opposite the opening 13. As each of the cups is brought against the inclined bottom 12, the bottom of the cup will project slightly beyond the bottom of the next cup above it owing to the inclined position of the cups, and the restraint due to the pressure of the rubber blocks 30 against the edges of the cups next the lowermost cup, enabling the edge of the cup to be

seized by the operator and drawn through the opening 13. The top of the lowermost cup while in position on the inclined bottom 12 will be pinched between the bottom 12 and the superimposed stack, holding the lowermost cup from longitudinal displacement.

I claim,

In a cabinet for a stack of collapsed drinking cups, a casing for inclosing the cups having an inclined bottom, and a slit between the lower edge of the bottom and one of the side walls of the cabinet, springs attached to said side wall, and rubber blocks carried by the free ends of said springs and bearing against the edges of the cups immediately above the lowermost cup in the stack, and means for varying the tension of said springs.

Dated this 12th day of June, 1912.

WILLARD E. SWIFT.
